UNITED STATES PATENT OFFICE.

RALPH S. CLARKE, OF WALPOLE, MASSACHUSETTS, ASSIGNOR TO BIRD MACHINE COMPANY, A CORPORATION OF MASSACHUSETTS.

BEATER FOR PAPER STOCK.

Application filed January 21, 1921. Serial No. 438,966.

To all whom it may concern:

Be it known that I, RALPH S. CLARKE, a citizen of the United States, residing at Walpole, in the county of Norfolk and State of Massachusetts, have invented certain new and useful Improvements in Beaters for Paper Stock, of which the following is a specification.

This invention pertains to beaters for paper stock and more particularly to those of the continuous type wherein a rotating screen or cylinder is employed to remove the finer or graded stuff.

The main object of the present invention is to provide means for agitating the cylindrical screen, or, in other words, to impart a vibratory motion to the screen in addition to the usual rotary movement about its axis, such vibratory movement causing a more ready inflow of the stuff into the screen and likewise acting to keep the screen openings clear.

A further object resides in the provision of means for regulating the outflow from the screen, such means being present in the shape of a box into which the screened stock flows, the box being provided with suitable dam boards.

The machine is illustrated in the annexed drawings wherein:

Fig. 1 is a top plan view of a portion of a beater with my improved screen applied thereto, together with the flow box;

Fig. 2 a vertical sectional elevation on the line II—II of Fig. 1;

Fig. 3 a transverse vertical section on the line III—III of Fig. 1;

Fig. 4 a detail sectional view on the line IV—IV of Fig. 5 of one of the eccentrics employed for raising the screen supporting arms; and

Fig. 5 a like view on the line V—V of Fig. 4.

In said figures 1 denotes the usual tub having a mid-feather or partition 2. The screen 3 is of cylindrical form having a closed head 4 adjacent the partition 2 while its opposite end is open and provided with a spider frame 5. The screen is secured to and rotatable with a shaft 6 journaled in suitable bearings 7 secured to a pair of spaced levers or arms 8 and 9. Said arms are fulcrumed upon a shaft or rod 10 which in turn is mounted in brackets 11 secured to

a cross bar or timber 12. Rotary motion is imparted to the screen from a driving pulley 13 through a sprocket chain 14 passing about sprocket wheels 15 and 16 respectively. The arms 8 and 9 incline upwardly toward their outer ends, see Fig. 2, and overlie a shaft 17 journaled in suitable bearings 18. Beneath each of the arms 8 and 9 the shaft is provided with an eccentric 19 about which passes a strap 20, the latter terminating in an upwardly extending bifurcated arm 21 beneath the elements of which extends the lever or arm 8 or 9, as the case may be. A through pin 22 forms a connection between the lever and eccentric strap. Motion is imparted to shaft 17 and consequently to the eccentrics 19 from a belt pulley 23 which is driven from any suitable source.

Located beneath each lever is a buffer or bumper, shown as formed from a block of rubber 24 having an overlying metallic cap 25 adapted to coact with a screw 26 adjustably mounted in the lever. Said buffers, as the levers are lowered, are put under compression and consequently assist the eccentrics when they reach that position where they begin to raise the levers. The levers and the supporting shaft 6 may be looked upon as a supporting frame for the screen, and in fact any form of frame work may be employed so long as it may be raised and lowered carrying the rotatable screen therewith.

The screen discharges through the lower portion of its open side into a valved discharge pipe 27 which empties into a box 28, the latter being provided with one or more dam boards 29 which control the level of the screened stock within the screen. For the most efficient operation of the machine it is found desirable to determine the correct level and then hold such level through the use of a dam board of proper height.

In operation the stock is caused to flow through the tub in the usual manner and direction and a rotary motion is imparted to the screen. At the same time it is raised and lowered through the eccentric mechanism above set forth. Such bodily raising and lowering of the screen causes a surging and suction action into and out of the screen of the stock undergoing treatment whereby a quicker intake of the properly graded stock is effected with a consequent removal of the

coarser particles from the screen openings as the screen is raised. The raising and dropping of the screen is independent of or in addition to the continuous rotary motion 5 of which the screen partakes and is found in practice to materially raise the efficiency of the screen. As the eccentrics near their limit of downward movement the screws 26 come in contact with the striker blocks 25 10 and cause a compression of the underlying rubber block 24. This arrangement prevents undue jar of the parts which might otherwise occur upon the falling of the frame, and also serves to assist the initial upward 15 movement of the frame under the action of the eccentrics. The compound movement of the screen, to-wit, its rotary movement about its axis and the up-and-down movement through the stream of stock as it is passed 20 around through the tub causes an inflow of the graded stock through the openings (which are coextensive of the screen surface but only partially so shown), to a degree much more rapid than where the screen is 25 alone rotated.

It is to be understood that in so far as the generic invention is concerned, to-wit, raising and lowering the screen while imparting rotary motion thereto, any mechanism which 30 will impart such dual motion may be employed, though that shown is simple and efficient.

What is claimed is,—

1. In a beater for paper stock, the combination of a tub; a hollow screen mounted upon a horizontal axis, said screen being located in line with the run of material through the tub; means for rotating the screen about its axis; and means for raising and lowering the screen while the same is being rotated.

2. In a beater for paper stock, the combination of a tub; a hollow screen mounted for rotation with its axis in a substantially 45 horizontal plane; and means for rotating the screen and simultaneously imparting to it an up-and-down movement.

3. In a beater for paper pulp, the combination of a tub; a hollow, perforate screen 50 mounted for rotation about a horizontally disposed axis, a portion only of the screen being submerged in the material passing through the tub; means for rotating the screen about its axis; and means for bodily 55 raising and lowering the screen, whereby the screen is caused to surge down into the stream of material passing in contact therewith.

4. In a beater for paper stock, the combination of a tub; a frame hinged at one end in line with the run of material through the tub; a hollow screen carried by said frame; means for rotating the screen; and means for raising and lowering the outer 65 end of the frame whereby the screen will be

periodically raised and lowered and a surging action of the same produced in the stream passing in contact with the screen.

5. In a beater for paper stock, the combination of a tub; a frame pivotally supported at one end; a shaft carried by the frame; a hollow screen carried by the shaft, the lower portion of the screen extending down into the path of the stream of material passing through the tub; means for rotating 70 said screen; an eccentric mechanism, for raising and lowering the outer end of the frame and consequently imparting to the screen an up-and-down motion in the stream. 75

6. In a beater for paper stock, the combination of a tub; a pair of levers fulcrumed at one end; a shaft mounted in bearings on the levers intermediate their ends; a hollow screen mounted upon the shaft, the lower portion of the screen extending into the tub 80 and into the path of movement of the stream passing therethrough; means for rotating the shaft and consequently the screen; a second shaft mounted in fixed bearings supported upon the tub; a pair of eccentrics 85 carried by said shaft, one beneath each of the levers; straps connecting said eccentrics with said levers; and means for rotating said shaft and the eccentrics and thereby imparting an up-and-down movement to the screen. 90

7. In a beater for paper stock, the combination of a tub; a pair of levers fulcrumed at one end; a shaft mounted in bearings on the levers intermediate their ends; a hollow screen mounted upon the shaft, the lower 100 portion of the screen extending into the tub and into the path of movement of the stream passing therethrough; means for rotating the shaft and consequently the screen; a second shaft mounted in fixed bearings supported upon the tub; a pair of eccentrics carried by said shaft, one beneath each of the levers; straps connecting said eccentrics with said levers; means for rotating said shaft and the eccentrics and thereby imparting an up-and-down movement to the screen; a buffer located in each lever, said buffer coming into action when the levers near their limit of downward movement. 105

8. In a beater for paper stock, the combination of a tub; a frame pivoted at one end; a hollow screen rotatably supported upon said frame; an eccentric mechanism for raising and lowering the frame; and a buffer cooperating with the frame, said buffer coming into action as the frame nears its limit of downward movement. 110

9. In a beater for paper stock, the combination of a tub; a hollow screen rotatably 115 mounted with reference thereto and adapted to have its lower portion submerged in the stream of stock passing through the tub, one side of the screen adjacent the outer portion of the tub being open; an outflow 120

125

pipe extending from the tub adjacent the lower portion of the screen; and a flow box into which the pipe discharges, said box being provided with means for maintaining the level of the stock therein and consequently within the tub.

10. In a beater for paper stock, the combination of a tub; a hollow, perforate screen having its lower portion submerged in the

stock flowing through the tub; and means for imparting a movement to the screen about its axis and simultaneously imparting a bodily movement to the screen in a direction transverse to the flow of material past the screen.

In testimony whereof I have signed my name to this specification.

RALPH S. CLARKE.
